UNITED STATES PATENT OFFICE.

FREDERICK R. SUNDERMAN, OF DETROIT, MICHIGAN, ASSIGNOR TO SUNDERMAN CORPORATION, OF NEWBURGH, NEW YORK, A CORPORATION OF NEW YORK.

CARBURETOR.

Application filed January 17, 1917. Serial No. 142,799.

To all whom it may concern:

Be it known that I, FREDERICK R. SUNDERMAN, a citizen of the United States, and a resident of Detroit, Wayne County, Michigan, have invented certain new and useful improvements in Carburetors, of which the following is a specification.

My invention relates to carburetors, and more particularly to carburetors for internal 10 combustion engines.

One of the objects of the invention is to provide a durable and efficient carburetor.

Another object of the invention is the provision of a non-adjustable carburetor that 15 will give efficient carburetion and proper regulation of the relative amounts of hydrocarbon and air utilized at starting and at the various speeds of the engine. By "non-adjustable" I mean a carburetor in which 20 the nozzles are not provided with adjustable needle valves or other means of regulating the opening for the hydrocarbon, and in which the air valve is not controlled in its operation by a spring; so that there is nothing of this nature to be tampered with or 25 adjusted.

My invention consists in the novel features and arrangement and construction of parts hereinafter shown and described in their 30 preferred embodiment and more particularly pointed out in the appended claims.

Further objects and advantages of the invention will more fully appear from the following description taken in connection with 35 the accompanying drawings, in which—

Figure 1 is a side elevation of a carburetor embodying the preferred form of my invention;

Figure 2 is a top plan view of the same;

Figure 3 is a longitudinal section taken on line 3—3 of Figure 2;

Figure 4 is a cross-sectional view taken on line 4—4 of Figure 1; and

Figure 5 is a sectional view taken on line 45 5—5 of Figure 2.

Referring to the drawings, and more particularly to Figs. 1 and 3,—1 is a carburetor having a mixing chamber for hydrocarbon fuel, in the form of a passageway 2, 50 which, in the preferred form of the invention as shown, is arranged horizontally and is rectangular in cross-section. The outer end of the passageway is provided with a cylindrical air intake extension 2' of greater 55 cross-sectional area than the passageway 2,

while the inner end is provided with a suitable vertical cylindrical extension or neck 3 having the well-known coupling flange 4 for securing it to a manifold. The neck of the carburetor is provided with a throttle valve 60 5 mounted on a swiveled pin 6, while the intake end of the passageway is provided with a "strangle" plate or valve 7 mounted on a swiveled pin 8, which is operated manually through any suitable connection to the 65 arm 8' secured to the outer end of the pin 8. This "strangle" plate is normally held open by a suitable spring 8", and the plate, as is understood, when used with a carburetor, is only closed momentarily for the 70 purpose of starting the engine or for causing it to pick up.

The passageway 2 is formed separate from its hydrocarbon tank 9, and is detachably secured thereto so that in case of a leak or 75 other trouble with the tank the same may be readily removed for inspection and repairs, without disturbing the connection of the carburetor to the manifold. The tank 9 is shown in the present form of the invention 80 as being cylindrical in cross-section and extending below the bottom wall of the passageway 2, and provided below the passageway with a bracket or flange 10 preferably formed integrally with the tank and by 85 means of which the tank is secured to the bottom wall of the passageway 2 by a screw 11.

The passageway 2 has discharging therein two nozzles 12 and 13 arranged in tandem 90 or spaced apart longitudinally of the passageway. These nozzles each preferably project upwardly from the bottom wall of the passageway and to a height substantially as shown in the drawings. These 95 nozzles in the present form of the invention, are screwed into the bracket 10 and communicate with orifices 14 and 15 leading to the tank, whereby the nozzles are secured to the tank and project slidably through the floor of the carburetor so that they may be removed with the tank when the latter is detached by removing the screws 11.

The passageway is further provided with a valve plate 16 pivoted or hinged at the 105 top or upper part of the passageway on a pin 17 supported in the side walls of the carburetor. In the preferred form of the invention as shown (Fig. 3) this valve plate is hinged sufficiently close to the upper wall, 110

or is so arranged, as to substantially prevent the flow of air above the same. The point at which the valve plate is hinged, in the embodiment of the invention shown, is 5 nearer the intake end of the carburetor than is the nozzle 13, and the plate extends inclined across the passageway inwardly and downwardly toward the inner nozzle 12 and has its free end normally resting upon the 10 bottom wall of the passageway so that the plate, when at rest, shuts off the passageway between the nozzles. While I prefer to use and have shown but two nozzles, obviously each may be replaced by a plurality, 15 thus dividing up the hydrocarbon discharge from each.

The valve plate has its free end bent upwardly from the general direction of the plate in a direction more parallel with the 20 general direction of the passageway where the plate is located. This bent portion, as shown, is preferably bent on a relatively large arc and has a short straight portion 18 at the extremity of its free end which terminates in proximity to the forward nozzle. In the form of the invention shown, and for a "one-inch carburetor," it preferably terminates within about a fourth of an inch of 25 said inner nozzle 12. This shape of the 30 plate and its termination from the inner nozzle is found to give the most satisfactory results in operation.

The valve plate 16, in the present embodiment of the invention (as shown in 35 Figs. 3 and 4) substantially fits the passageway so as to substantially prevent the flow of air past the same when in its normal position, thus greatly increasing the effect of the suction of the engine on the inner 40 nozzle by throwing the full suction, so to speak, on this nozzle, while substantially preventing the effect of the suction on the outer nozzle 13 so long as the plate substantially 45 closes the passageway, and when the plate is slightly lifted, as at slow speeds, the effect of the suction of the engine on the forward nozzle continues to be substantially increased by the substantial throttling 50 action of the plate on the incoming air, while the effect of the suction on the outer nozzle is extremely slight, if effective at all, depending upon the height and location of this nozzle with respect to the inclined 55 valve plate. The plate is located, as shown in Fig. 3, directly above the outer nozzle 13, so that when the plate is lifted, a portion of the incoming air is directed in a converging stream down upon this nozzle, and the whole 60 of the incoming air and the atomized hydrocarbon from this nozzle are directed in a converging stream inwardly toward the inner nozzle 12. The plate thus produces a venturi effect when lifted in operation, and also serves to direct the mixture from 65 the outer nozzle 13 downwardly, and to

cause it to flow close to the bottom wall of the passageway until it passes the inner nozzle 12, while the fuel discharged from the inner nozzle is directed more vertically.

Above the curved end of the swivel plate 16 the fuel passage is provided with an upward convexed surface, and in the present embodiment of the invention this is provided by a downwardly curved or convexed plate 19 attached by screw 20 to the shell of the chamber. The plate is so located and the curvature is preferably such that the lowermost point of the convexed surface is located directly above the curved end of plate 16. It has been found that when this curved surface is used in conjunction with the plate 16, greater efficiency and more satisfactory operation of the carburetor is obtained.

Any suitable float and valve may be utilized in the tank shown, but I prefer the construction herein shown (Figs. 4 and 5), consisting of a hollow metal float 22 carried by an arm 23 which is pivoted at 24 and is provided with a forked end 25, these forks fitting an annular grooved or reduced portion 26 of a plunger 27 the lower end of which fits in a nipple 28 having a passage 29 for the flow of gasoline, closed by a ball valve 30 engaged and adapted to be seated by plunger 27 when the float 22 is swung on its pivot. In order to inspect the valve 30, I provide an orifice or opening 31 directly in alignment with the plunger 27, closed by a tap screw 32. The pivot pin 24 for the float lever 23 extends through a projection 33 (Fig. 2) on the outside of the carburetor, and the pin or wire 24 projects outwardly so that when it is desired to inspect the valve this pin may be withdrawn, the screw 32 removed, and the plunger and valve inspected or removed through this opening, or by removing the nipple 28, as may be most convenient.

The operation of the preferred form of the invention as shown is as follows:—

If the "strangle" plate 7 is utilized, in starting the engine this is closed by the operator, whereupon, as the engine is turned over, the suction commences the discharge of hydrocarbon from the forward nozzle 12, and thereupon lifts the valve plate 16 and causes nozzle 13 to discharge, the hydrocarbon from the nozzle 12 being sucked forward in a substantially vertical direction and the hydrocarbon from the nozzle 13 being guided more or less downwardly and along the bottom wall of the passageway until it passes the nozzle 12. As soon as the engine picks up, the operator releases the "strangle" valve 7 and the plate 16, according to the speed of the engine, drops to a lower position than that assumed when the "strangle" plate is closed. Assuming that the speed of the engine at this time is very slow, as is generally the case, the free edge of the valve plate 16

will then lie say an eighth of an inch above the bottom wall of the passageway, thus, while not substantially closing the passageway, it substantially throttles the flow of incoming air so as to continue the increased effect of the suction on the forward nozzle 12, and so as to substantially check or allow only a feeble discharge of the hydrocarbon from the outer nozzle 13, or entirely prevent the same, depending upon the position and height of said nozzle. If there is a feeble discharge from this nozzle, as is the case when the parts are arranged as shown, the incoming hydrocarbon mixture is deflected by the plate 16 downwardly along the lower wall of the carburetor, and, due to the bent extremity of the plate, is caused to continue to flow in this direction in a current below the discharge point of the forward nozzle 12. Thus, at very low speed, a rich mixture is supplied to the engine, and as the engine speeds up, the increased suction continues to lift plate 16, thus increasing the suction on the outer nozzle 13 and admitting an additional amount of air.

The incoming air is caused, by the lower surface of the plate 16, to converge on the nozzle 13 and the plate 16 continues to direct this mixture along the lower part of the passageway, but at an increasing depth, depending upon the height that the valve is lifted, while the increased suction and inflowing air cause the discharge of hydrocarbon from the inner nozzle 12 to be deflected more horizontally than at slower speeds, but the discharge from this nozzle continues to flow into the neck of the carburetor above that from the outer nozzle 13. The deflecting plate 19 in this form of the invention, in the position shown, also serves as a deflecting plate for the discharge from nozzle 12 at low speeds.

It will thus be seen that these features provide a carburetor with considerable flexibility of operation,—i. e., proper regulation of the relative amounts of hydrocarbon and air, and the proper vaporization of the hydrocarbon at starting and for its various speeds, all automatically and without any parts to be adjusted.

Having understood the construction and features of operation of the preferred form of my invention herein shown, it will be obvious to those skilled in the art that various modifications and changes may be made therein without departing from the spirit or scope of my invention. For example, it is desirable, for the purpose of quick and smooth starting and smooth operation at low speeds, even where the "strangle" plate 7 is utilized, and more so where such plate is not utilized, to have the valve plate 16 substantially close the passageway between the two nozzles, and for the proper distribution of the hydrocarbon in the passageway it is desirable that the nozzles discharge from the

bottom wall of the passageway and have the relative location with respect to the other parts shown. But it will be obvious that some features and advantages of the invention from its broader aspect will be retained with modifications of these parts, and I aim in the appended claims to cover such modifications, and do not wish to be understood as limiting the invention other than as indicated in the appended claims.

Having thus described my invention, what I claim as new and desire to secure by Letters Patent, is:—

1. In a carburetor, the combination of a substantially rectangular horizontal passageway, a hydrocarbon nozzle discharging within the passageway at a point substantially above the lower wall thereof, a second nozzle discharging within the passageway at a point further inward than the first, a valve plate in the passageway hinged at the upper wall of the passageway and movable upwardly and inwardly and adapted to be acted upon by suction to be swung upwardly and inwardly by and according to the suction of an engine, said plate, when in normal position and when slightly lifted from normal position, extending inclined downwardly and inwardly from its hinge across the passageway toward the second nozzle and beyond the first to such a distance that its free end is sufficiently below the discharge opening of said first nozzle to substantially check the discharge of said first nozzle while the suction on the second nozzle is increased by said plate due to the latter's substantial throttling action on the air, whereby strong suction on the inner nozzle is attained at slow speeds and the discharge of the outer nozzle substantially retarded until the suction on the plate has been increased as at higher speeds.

2. In a carburetor, the combination of a substantially rectangular horizontal passageway, a hydrocarbon nozzle discharging within the passageway at a point substantially above the lower wall thereof, a second nozzle discharging within the passageway at a point further inward than the first, a valve plate in the passageway hinged at the upper wall of the passageway and movable upwardly and inwardly and adapted to be acted upon by suction to be swung upwardly and inwardly by and according to the suction of an engine, said plate, when in normal position, extending inclined downwardly and inwardly from its hinge across the passageway toward the second or inner nozzle and to the lower wall of the passageway and substantially closing the passageway to prevent said first or outer nozzle being brought into operation, and to throw the full suction of the engine on the second or inner nozzle by substantially excluding the admission of air.

3. In a carburetor, the combination of a passageway for hydrocarbon fuel, a nozzle discharging within the passageway, an air admission valve plate for controlling the flow of air to the nozzle, said plate hinged at one end to swing within the passageway and adapted to be acted upon by the suction of an engine to be lifted upwardly and inwardly according to the suction, and extending across the passageway a sufficient distance to regulate the supply of air past

the nozzle according to the suction, and having its free end bent upwardly from the general direction of the body of the plate, said passageway being provided with an upper surface which is in general convexed and located above the free end of said plate to co-operate with said bent free end. 15

In testimony whereof, I have signed my name to this specification.

FREDERICK R. SUNDERMAN.
